US00D605769S

(12) **United States Design Patent**
Sjursen et al.

(10) **Patent No.:** US D605,769 S
(45) **Date of Patent:** ** Dec. 8, 2009

(54) **HEARING AID PART**

(75) Inventors: **Walter P. Sjursen**, West Windsor, NJ (US); **Michael DeSalvo**, Princeton, NJ (US); **Hassan A. Mohamed**, Bayonne, NJ (US); **Alyssa R. Needleman**, San Diego, CA (US)

(73) Assignee: **Songbird Hearing, Inc.**, North Brunswick, NJ (US)

(**) Term: **14 Years**

(21) Appl. No.: **29/320,431**

(22) Filed: **Jun. 26, 2008**

(51) **LOC (9) Cl.** 24-99

(52) **U.S. Cl.** **D24/174**

(58) **Field of Classification Search** D24/173-175, D24/182, 106; D14/205, 223, 224, 249; 381/23.1, 312, 322, 323, 324, 328, 329, 330, 381/380, 381; 181/129, 130, 134, 135, 137

(57) **CLAIM**

We claim the ornamental design for a hearing aid part, as shown and described.

DESCRIPTION

FIG. 1 is a perspective view of a hearing aid part, showing the design with an attached cable and earpiece;

FIG. 2 is a top view thereof;

FIG. 3 is a bottom view thereof;

FIG. 4 is a right side view thereof;

FIG. 5 is a left side view thereof;

FIG. 6 is a back end view thereof; and,

FIG. 7 is a front end view thereof.

The features shown in broken lines represent environment and do not form part of the claimed design.
